EDWARD S. CAREY, OF MILWAUKEE, WISCONSIN, ASSIGNOR, BY MESNE ASSIGNMENTS, TO
ARTHUR K. READING, OF MAYVILLE, WISCONSIN

METHOD OF RADIATOR MANUFACTURE

Application filed April 24, 1930. Serial No. 446,965.

This invention relates to improvements in methods of radiator manufacture. This application is a companion to my applications of even date herewith and relating respectively to an application for use in practice of the method herein disclosed and a radiator which is a product of such method.

It is the object of the present invention to provide a novel and improved method where-
10 by fins of sheet metal may be fused in heat conducting relation upon a suitable conduit for fluid. It is my further object to provide means enabling the formation of such conduit in any desired contour through a casting op-
15 eration whereby the formation of the central conduit and the fusing of the fins thereto are accomplished simultaneously. It is my fur-
ther object to provide a method for making up in any desired length radiator units em-
bodying the features disclosed herein and in
20 the product application aforesaid, while em-
ploying the sheet metal radiator fins in co-
operation with intervening die plates as a
mould within which to cast the central body
25 in which the steam duct or conduit is formed.

In the drawings:

Figure 1 is a perspective view of the assem-
bled fins and die plates constituting a mould
in accordance with the practice of the pres-
30 ent invention, certain of the die plates be-
ing broken away to expose the surface of one
of the fins.

Figure 2 is a view in transverse section on
35 the plane indicated at 2-2 in Figure 1 and
showing that stage of the operation in which
pouring of molten metal into the mould has
commenced.

Figure 3 is a section similar to Figure 2
40 showing the partially completed product with
the die plates or spacing plates withdrawn
and the core member partially withdrawn.

Figure 4 is a view in fragmentary perspec-
tive showing a modified form of mould for
45 use in connection with the method of the
present invention.

Figure 5 is an end elevation of a radiator
such as will be produced by the form of mould
shown in Figure 4.

50 Like parts are identified by the same ref-

erence characters throughout the several views.

Referring first to Figure 3, it will be noted that the completed article made in accordance with the process herein disclosed, is to include a central body 5 about the periphery of which sheet metal radiating fins 6 are fused. The internal contour of the body 5 is preferably cylindrical to comprise a steam passage 7. The external contour, however, is 55 preferably elliptical or oval as indicated by the openings shown in Figure 1. The object of this external contour is to promote the transverse flow of gases between fins 6.

The fusion between the body 5 and the fins 6 is accomplished by casting the body 5 within openings 8 within the fins and slightly larger openings 9 of the desired external contour. The openings 9 are formed in the complementary margins of die plates 10 and 11 60 which are arranged in vertical stacks inter-
leaved with fins 6 as shown in Figures 1 and
2. The die plates preferably project beyond
fins 6 as shown in Figure 1 and are provided
therebeyond with openings such as the dove-
tailed slots 12 which register vertically
70 throughout the stack of die plates thereby
permitting the use of a tool for engagement
with all of the die plates of each stack to dis-
engage the whole series thereof simultane-
ously from the completed casting.

Arranged to project vertically downwardly
through the registering holes 8 and 9 in the
fin plates and die plates respectively is a core
member 15 which may be withdrawn verti-
cally as shown in Figure 3. In order to pre-
vent the cast body 5 from shrinking upon the
core member 15 to such an extent as to make
withdrawal of the core member impossible, I
encase the core member 15 in a jacket 16 com-
prising a sleeve of asbestos paper or the like.
I have even used asbestos board having a
corrugated bore as shown in the drawings,
although this is not necessary. Any asbestos
paper of reasonable thickness is sufficiently
compressible to permit the core 15 to be with-
drawn from its socket 18 and from the cast-
ing 5. Water will then soften the asbestos
core and permit it readily to be washed out 95
100

of the bore remaining in the casting as a steam conduit therethrough.

With the die plates 10 and 11 and the interleaved sheet metal fin plates 6 assembled in a stack, as best shown in Figures 1 and 2, molten metal which preferably is identical with that used in the fin plates 6 and is preferably highly conductive of heat, such as aluminum, is poured into the openings 8 of the fins and the openings 9 formed by the complementary notches in the margins of the die plates 10 and 11. It should be stated that the line of division between the die plates may obviously coincide with either the major or minor diameters of the oval or elliptical openings 9 therein. The use of die plates as disclosed permits the manufacture of cast bodies 5 having a great variety of external contours.

As the hot metal is delivered into the openings in the stack of plates as shown in Figure 2, it flows outwardly between the fins 6 until stopped by the combined action of the die plates and the cooling of the molten metal due to dissipation of heat into the fins 6. The fin plates 6 are sufficiently thin so that the margins thereof about the openings 8 will melt and fuse with the body of cast metal. In thus delivering up heat to the fins, and particularly because of the close spacing of the fins and the fact that they extend completely around the body of cast metal to take heat from all portions thereof, it will be found that the cast metal, if poured at the correct temperature, will solidify very quickly and for this reason will not tend to seep between the fins and die plates in the assembled stack.

Thus when the cast body 5 has solidified with the fin plates 6 fused therein, there is nothing except a certain degree of contraction of the cast body to prevent free withdrawal of the die plates from between the fins. To overcome any friction resulting from such contraction as occurs, I have provided the openings or slots at 12 with which a dove-tailed member may be engaged to withdraw the plates.

During the operation of withdrawal, the completed radiator section is held stationary by engagement of the core 15 in socket 18. After the spacing and forming plates 10 and 11 are withdrawn, core 15 is withdrawn, the sheet 16 is washed out or otherwise removed, and the radiator section is threaded for pipe connections or is cut into smaller sections which are individually threaded.

Obviously the length of radiator section which may be made in accordance with this invention is limited only by the apparatus available and the length of possible flow of molten metal through the assembled stack of plates before solidification occurs.

Where the desired length of the mould and the character of the desired material to

be employed are such that the molten material cannot reasonably be expected to flow the entire length of a vertical mould such as that shown in Figure 1, I may use the form of mould shown in Figure 4 which is identical with that shown in Figure 1 with the exception that the stack of laminations extends horizontally instead of vertically, each lamination, or at least selected laminations, being slotted to provide a sufficient opening 75 for the introduction of the molten material to the communicating apertures in the interior of the mould.

The slots of the fin plates 6, if these be used, may be made narrower than the slots 80 in the spacer plates 10 and 11 so that the margins of the fin plates will be fully embedded in the tongue 20 of the cast body 5, as shown by dotted lines in Figure 5.

The funnel 21 may be used to guide into the aligned slots of the mould laminations the body of metal at 22 in the trough shaped ladle or pouring device 23. Such body of metal is preferably just sufficient to fill the cavity within the mould and due to the fact that the molten material is poured into the side of the mould it has a very short distance to flow. Thus, notwithstanding the extent to which the centrally projecting margins of the films will carry off the heat, the molten material will adequately fill a mould of any length.

In all other respects the apparatus shown in Figure 4 may correspond with that shown in Figure 1 and Figure 2. Obviously other variations in form are possible with the scope of the present invention.

I claim:

1. The method of casting which consists in assembling a stack of laminations having communicating apertures corresponding at each point to the cross section of the desired casting and pouring laterally into said apertures the material to be cast, whereby edges of certain of the laminations are fused and united with the casting.

2. The method of casting which includes the assembly in a horizontally elongated series, of a set of laminations having communicating apertures and upwardly opening slots, and pouring into the slots of said laminations the material to be cast in the apertures thereof, whereby edges of certain of the laminations are fused and united with the casting.

3. The method of manufacturing radiator units, which method comprises the steps of preparing a plurality of sheet metal plates to form radiating fins and providing each such fin plate with an opening of predetermined dimensions; preparing a plurality of pairs of separable spacing and die plates and providing pairs of such plates at their meeting edges with an opening of larger dimensions; assembling the fin plates and pairs

of spacing and die plates in alternation with the openings therein in communication to form a casting cavity, with the margins of the fin plates abutting the openings therein extending into the said cavity; positioning a 5 core member longitudinally in the said cavity to provide a conduit; filling the cavity with molten metal whereby to fuse the said extending margins of the fin plates and form 10 an integral structural radiator unit comprised of a longitudinal body and a plurality of radially disposed radiating fins; and withdrawing the spacing and die plates from the said unit.

15 4. The method of manufacturing radiator units, which method comprises the steps of preparing a plurality of sheet metal plates to form radiating fins and providing each such fin plate with an opening of predetermined dimensions; preparing a plurality of 20 pairs of separable spacing and die plates and providing each pair of such plates at their meeting edges with an opening of larger dimensions; assembling the fin plates and pairs 25 of spacing and die plates in alternation with the openings therein in communication to form a casting cavity, with the margins of the fin plates abutting the openings therein extending into the said cavity; positioning 30 a core member longitudinally in the said cavity to provide a conduit; filling the cavity with molten metal whereby to fuse the said extending margins of the fin plates and form an integral structural radiator unit 35 comprised of a longitudinal body and spaced, radially disposed radiating fins; and withdrawing the spacing and die plates from the said unit.

5. The method of manufacturing radiator units, which method comprises the steps of 40 preparing a plurality of sheet metal plates to form radiating fins and providing each such fin plate with an opening of predetermined dimensions; preparing a plurality of 45 pairs of separable spacing and die plates and providing each pair of such plates at their meeting edges with an opening of larger dimensions; assembling the fin plates and pairs 50 of spacing and die plates in alternation with the openings therein in communication to form a casting cavity, with the margins of the fin plates abutting the openings therein extending into the said cavity; positioning a core member longitudinally in the said cavity 55 to provide a conduit; filling the cavity with molten metal whereby to fuse the said extending margins of the fin plates and form an integral structural radiator unit comprised of a longitudinal body and a plurality of 60 radially disposed radiating fins, and withdrawing the spacing and die plates and the core member from the said unit.

6. The method of manufacturing radiator units, which method comprises the steps of 65 preparing a plurality of sheet metal plates

to form radiating fins and providing each such fin plate with an opening of predetermined dimensions; preparing a plurality of pairs of separable spacing and die plates and providing each pair of such plates at their meeting edges with an opening of larger dimensions; assembling the fin plates and pairs of spacing and die plates in alternation with the openings therein in communication to form a casting cavity, with the margins of the fin plates abutting the openings therein extending into the said cavity; positioning a covered core member longitudinally in the said cavity; filling the cavity with molten metal whereby to fuse the said extending 80 margins of the fin plates and form an integral structural radiator unit comprised of a longitudinal body and a plurality of radially disposed radiating fins; withdrawing the spacing and die plates from the said unit; 85 and withdrawing the core member and its covering to provide a conduit in the radiator unit.

7. The method of manufacturing radiator units, which method comprises the steps of preparing a plurality of thin, fusible, sheet metal plates to form radiating fins and providing each such fin plate with an opening of predetermined dimensions; preparing a plurality of pairs of thicker, non-fusible, separable spacing and die plates and providing pairs of such plates at their meeting edges with an opening of larger dimensions; assembling the fin plates and pairs of spacing and die plates in alternation with the openings therein in communication to form a casting cavity, with the margins of the fin plates abutting the openings therein extending into the said cavity; positioning a core member longitudinally in the said cavity to provide 90 a conduit; filling the cavity with molten metal whereby to fuse the said extending margins of the fin plates and form an integral structural radiator unit comprised of a longitudinal body and a plurality of radially 95 disposed radiating fins, and withdrawing the spacing and die plates from the said unit.
